LAVATORY TOP

Frank M. Crook, Toledo, Ohio, assignor to Toledo Desk
& Fixture Corporation, Maumee, Ohio, a corporation of Ohio

Application June 11, 1953, Serial No. 25,436

Term of patent 7 years

(Cl. D4—2)

FIG. 1.

FIG. 2.

Fig. 1 is a perspective view of a lavatory top embodying my new design, and

Fig. 2 is an enlarged fragmentary perspective view of the top showing the recessed configuration of the splash back.

The rear of the lavatory top is plain.

The stippling indicates color contrast.

The dominant features of the design reside in the portions shown in solid lines.

I claim:

The ornamental design for a lavatory top, as shown and described.
